UNITED STATES PATENT OFFICE.

ERICH HILLIGARDT, OF AKRON, OHIO, ASSIGNOR TO LUFTSCHIFFBAU ZEPPELIN GESELLSCHAFT MIT BESCHRAENKTER HAFTUNG, OF FRIEDRICHSHAFEN, GERMANY.

CONTROLLING DEVICE FOR BALLAST CONTAINERS IN AIRSHIPS.

Application filed September 30, 1925, Serial No. 59,453, and in Germany October 11, 1924.

My invention relates to a device for controlling whether a container for liquid is full or empty and more especially with regard to ballast containers in airships.

5 There are different kinds of ballast containers in airships. Some are for gradual discharging of their contents, others are arranged so as to empty all the ballast contained in one moment. I am referring to 10 the latter kind, and the object of my invention is to provide means for indicating at a certain spot within the airship—for example in the control car—whether such container is still full or whether its contents was 15 discharged. The containers for momentary discharging of the ballast generally are made of an inner watertight fabric with an outer sleeve of ordinary fabric. As long 20 as the inner watertight container is full of water or other suitable ballast, its walls press against the outer sleeve.

According to my invention I make use of 25 this pressure for closing an electric contact so that a current may pass through wires extending from the ballast container situated 30 at any suitable place within the airship to the control car. Here this current will light an electric lamp, constantly or only when a special contact in the car is closed, or it will 35 operate any other suitable indicating means. In case the ballast container was emptied by means of a special device, the pressure on the outer sleeve will disappear and the electric current used for lighting the lamp 40 or for operating another indicating means in the car is interrupted, so that when closing the contact in the car, the lamp will not light or the means not operate; thereby indicating that the corresponding container is empty.

Having given a general description of my invention, I now want to point it out in detail, referring to the drawings which represent an example embodying my invention.

Fig. 1 is a vertical section through a ballast container filled with water.

Fig. 2 is the same but showing an empty container. Both figures are partly broken up.

Fig. 3 is a section through the electric contact which is situated on the outer sleeve of the container.

Fig. 4 is longitudinal section through an airship.

In Fig. 1 the inner container B presses against the sleeve A, thereby closing the electric contact C. In Fig. 2 container B is empty so that it is out of touch with contact C.

The contact arrangement consists of a casing c, connected to the sleeve A. Wires d and e lead into this casing through a tube f surrounded by a sleeve g fitting into a nipple h. The wires are connected to clamping screws i and k, respectively, fastened to wall m. On the other side of this wall contacts n and o are provided, n being in metallic connection with k and o with i. Contact o has the shape of an elastic spring, 70 extending upwardly and opposite of n. An elastic membrane p is stretched so that an inward pressure will press it against spring o, thereby bringing o into contact with n. The portion of the contact arrangement 75 which is confined by wall m on one side and membrane p on the other side is made water tight and gas tight. I prefer to make membrane p out of leather. Outside of membrane p a bearing q is provided into which fits a pushing rod s having a disc-like outer end r and an inner rounded end t. A spring u serves to press rod s outwardly. In case the container B be filled it presses against disc t, thereby 80 compressing spring u and pushing end t of rod s against membrane p, which causes spring o to come into contact with contact n, thus creating electric contact between wires e and d, so that a current may flow 85 through and operate an indicator situated at any place where-to wires e and d may lead, for example the control car of the airship. Such indicating means are shown for example at D but they may be of any kind and well known construction.

I do not want to limit myself to the example described or shown in the drawings as many variations will occur to those skilled in the art.

What I claim is:

1. In an airship a container for ballast, a control car situated remote from said ballast container; an electric contact arrangement adapted to be operated by pressure resulting from the contents of said con-

- tainer and means for operating an indicator depending on said electric contact.
2. In an airship a container for ballast; a control car situated remote from said ballast container; an electric contact arrangement adapted to be operated by pressure resulting from the contents in said container; said electric contact arrangement having a watertight compartment in which the metallic parts for contact are provided; and means for indicating in said control car whether said contact is closed or open.
3. In an airship a container for ballast; a control car situated remote from said ballast container; an electric contact arrangement adapted to be operated by pressure resulting from the contents in said container; said electric contact arrangement having a gas tight compartment in which the metallic parts for contact are provided; and means for indicating in said control car whether said contact is closed or open.

ERICH HILLIGARDT.
